SOAKING PIT COVER AND METHOD OF
MAKING SAMEFrank Jantek and George G. Lloyd,
Pittsburgh, Pa.

Application July 3, 1942, Serial No. 449,634

3 Claims. (Cl. 29—148)

The present invention relates to the specific features of improvement in soaking pit covers and to a novel method whereby such covers may be quickly and economically fabricated. The various features and advantages of the invention will be apparent from a consideration of the following detail disclosure, the accompanying drawings and the appended claims.

In the drawings:

Figure 1 is a plan view illustrating one step in the novel method of fabricating the improved cover;

Figure 2 is a similar plan view illustrating the cover after the same has been put to use in the soaking pit;

Figures 3 and 4 are sectional views through a soaking pit taken on the correspondingly numbered section lines of Figure 2;

Figure 5 is an enlarged detail illustrative of the manner of uniting longitudinal and transverse frame members of the improved soaking pit cover; and

Figure 6 is a section on line VI—VI of Figure 5, the broken lines showing the original cross sectional contour of the rolled steel section from which the cover frame is fabricated.

Heretofore soaking pit covers have usually comprised cast iron frames of sectional form bolted together and lined with suitable firebrick. Such cast iron frames warp or become distorted in practice under the influence of the intense heat to which the covers are subjected during the heating or reheating of ingots charged to the soaking pit.

The chief characteristic of the present invention is that the soaking pit frame is constructed of a plurality of rolled steel flanged sections, securable in stock sizes, and united in such manner that an inward camber is imparted to said sections as later set forth.

While not limited thereto, relatively heavy H-sections are preferably employed and the flanges thereof are cut away to suit the dimensions of the pit to be covered. In fabricating the soaking pit cover according to the invention, we regard it essential to impart an inward camber to the rolled steel frame members and to integrally secure the thus cambered parts together, preferably by welded joints at corners. This method of manufacture thus places the longitudinal and transverse frame members under an internal strain acting inwardly due to such cambering of the parts. After the cover is subsequently put in service and subjected to a high degree of heat during the treatment of

ingots in the soaking pit, the intense heat stresses the metal members in a direction opposite to that in which they were prestressed by the cambering. Thus the forces of expansion in normal operation are neutralized and the frame members of the cover straighten out.

As shown in Figure 1, in building the improved pit cover according to our method, we provide a pair of longitudinal frame members 10—10 and transverse members 12—12. These members are fabricated from stock size commercial rolled steel H-sections which originally have the cross sectional contour indicated by the broken lines in Figure 6. Portions of the top and bottom flanges are cut off so as to leave the metal shown by the hatched portions in Figure 6.

The ends of the top and bottom flanges of the longitudinal members are cut or beveled off, for example, as indicated along the oblique line 14 in Figure 5. Similarly the ends of the transverse members 12 are cut off on an oblique line, as indicated by the line 16 in Figure 5. The line 16 is a substantially true 45 degree miter, whereas the line 14 makes an angle of less than 45 degrees with the parallel edges of the flanges of the member 10. Thus the oblique lines 14 and 16 converge outwardly toward the corner where the members 10 and 12 meet. This converged arrangement of the opposed beveled edges of the top and bottom flanges facilitates the cambering of the sections, which is regarded as one of the outstanding essential characteristics of the invention. The contiguous ends of the sections 10 and 12 are then welded together at the four corners, the welds being indicated at 18. After the top and bottom flanges of all sections have been welded at the four corners, a substantially square or rectangular frame will have been produced, such as shown in Figure 1, it being noted,

however, that the magnitude of inward camber in the drawings has been exaggerated for illustrative purposes. The inner area bound by the thus cambered frame is then filled with an arched brick lining, indicated at 20. The end skewbacks 22 of the brickwork arch rest on the lower inner flanges of the frame members and also react horizontally against the web portions 24. In some cases these web portions will have bars 26 welded or otherwise secured thereto to interfit with grooves formed in the skewback brick so as to interlock the same therewith. After the improved soaking pit cover made in accordance with our improved method has been subjected to the intense heat of a soaking pit furnace during the normal treatment of ingots, the

frame members will be expanded to a sufficient extent so as to practically straighten them out to the condition shown in Figure 2, wherein it is noted that the originally cambered members now form a substantially true square or rectangular frame.

While we have described the exact steps in the method and precise structural features which practical adoption of the invention has shown to be highly advantageous, it is to be understood that various modifications in the manufacturing procedure and modifications as to features of structure and adoption of mechanical equivalents may be resorted to by those skilled in the art without departing from the spirit and scope of the invention as defined in the appended claims.

We claim:

1. A soaking pit cover comprising a substantially rectangular frame composed of longitudinal and transverse rolled steel sections, each having top and bottom flanges united by an integral web, the ends of the flanges being welded to one another and each section being inwardly cambered so as to compensate for the expansion of the cover when in use, and a body of brickwork filling the space between the webs of the several sections.

2. A soaking pit cover comprising a substantially rectangular frame composed of longitudinal and transverse rolled steel sections, each having top and bottom flanges united by an integral web, the ends of the flanges being cut off at angles oblique to their parallel edges, welded joints uniting said flanges along their contiguous oblique edges, said sections each being inwardly cambered so as to compensate for the expansion of the cover when in use, and a body of brickwork filling the space between the webs of the several sections.

3. The method of making a rectangular soaking pit cover, which comprises providing respective pairs of straight longitudinal and transverse rolled steel flanged H-shaped sections, cutting off parallel marginal portions from the outer edges of each of said flanges throughout the respective lengths thereof, cutting the ends 15 of the thus-altered flanges along converging mitre-like oblique lines, imparting a camber to each of said sections in the direction of convergence of said lines, and welding the oblique edges of the longitudinal and transverse sections to one another to retain the respective 20 cambers imparted thereto.
